Primary Examiner — Mary Ann Calabrese(74) *Attorney, Agent, or Firm* — Fish & Richardson P.C.(57) **CLAIM**

The ornamental design for a table, substantially as shown and described.

DESCRIPTION

FIG. 1 is a perspective view of a table.

FIG. 2 is a front view of the table of FIG. 1.

FIG. 3 is a rear view of the table of FIG. 1.

FIG. 4 is a right side view of the table of FIG. 1.

FIG. 5 is a left view of the table of FIG. 1.

FIG. 6 is a top view of the table of FIG. 1; and,

FIG. 7 is a bottom view of the table of FIG. 1.

The broken lines adjacent to the solid lines on the table top represent the boundaries of the claimed portion of the design and form no part thereof. All other broken lines represent portions of the table that form no part of the claimed design.

1 Claim, 7 Drawing Sheets(56)
